UNITED STATES PATENT OFFICE.

THOMAS A. QUINLAN, OF BROOKLYN, NEW YORK, ASSIGNOR TO F. L. SMITH MACHINE COMPANY, INCORPORATED, OF NEW YORK, N. Y., A CORPORATION OF NEW YORK.

PROCESS OF TYING.

Application filed May 2, 1922. Serial No. 558,084.

To all whom it may concern:

Be it known that I, THOMAS A. QUINLAN, a citizen of the United States, and a resident of New York, borough of Brooklyn, in the 5 county of Kings and State of New York, have invented certain new and useful Improvements in Processes of Tying, of which the following is a specification.

This invention relates to bow ties and to 10 processes for tying the same. The object of my improvements is to provide a bow tie simple in character and pleasing in appearance, and a process therefor reliable in result.

15 To these ends my improvements comprise features illustrated in the drawing accompanying this specification, wherein Figures 1 to 3 inclusive represent in perspective successive steps in the performance of my 20 process and Fig. 4 represents in perspective the completed bow tie.

For the purpose of adequate description my improved process is described as comprising a series of steps, but such steps are 25 not necessarily performed in the order named, as several of said steps may be performed simultaneously and some may be performed in more than one order.

Also while the improved bow tie of my 30 process may be formed from a length of ribbon or string just adequate for the purpose, it may be, and preferably is formed, when a plurality of successive bow ties is desired, from an end portion of a continuous 35 ribbon, as from a spool or roll thereof. Also while said bow tie may be formed without any relation to a package or box, said tie, for purposes of illustration, is shown as employed for joining opposite portions of a 40 ribbon encircling a box or package A.

45 Directing attention now to the drawing, in Fig. 1 thereof the left end portion 2 of the ribbon is folded over to the right, preferably slightly rearwardly, then the right end or continuous portion 3, from a source of supply not shown is folded to the left over portion 2. Then said portion 3 is folded back to the right forming loop or bow 4, then back to the left forming loop 5. In 50 some cases I prefer to complete the bow tie with these two loops or bows 4 and 5, but in other cases I form a third loop or bow 6 by folding the ribbon back again to the right, Fig. 1.

55 These and the later steps may all be per-

formed with the fingers of the operator, but simple tools or a machine may be employed if desired. In the drawing loop 4 is shown as folded about hook 7, loop 5 about bar 8 and loop 6 about hook 9. A convenient 60 manner of forming said loops is to loop portion 3 of the ribbon about bar 8, and then to engage opposite portions of the ribbon adjacent said bar by means of hooks 7 and 9 and then simultaneously to draw those hooks 65 to the left thereby forming loops 4 and 6.

In any case after the two or three loops are formed, either successively or partly simultaneously, the next step is the folding of the free end 2^a of the underlying portion 2, 70 forwardly over the loops, Fig. 2, and then, by means of the fingers or a simple gripping tool, as 10, passing said end 2^a under the body portion 2 thereof, through first loop 4 and under the other loops 5 and 6, Fig. 3, 75 thereby forming loop 11 enclosing the three loops 4, 5 and 6. Then said end 2^a is drawn to the right, partly closing up loop 11 and, if tools 7, 8 and 9 have been employed, said tools are then withdrawn from engagement 80 with the respective loops. Then end 2^a and loop 5 are drawn in opposite directions, said end to the left and said loop to the right, to tighten the knot and complete the bow tie, 85 Fig. 4. It will be understood that the showing of Fig. 4 is somewhat open in character, to show clearly the construction of the bow tie and that in practice said knot portion is drawn tighter than shown, to hold the bow tie securely in its finished condition. 90

I claim:

1. That improvement in the art of forming a bow tie comprising the following steps: Folding over to the right the left end portion of a ribbon or string, folding the right end portion of said ribbon to the left over the left end portion, folding said right end overlying portion to the right thereby forming a loop or bow, then folding said end to the left, forming a second loop, then 95 folding the left underlying portion forwardly over said loops, passing the end of said underlying portion under the body portion thereof, then through said first loop, and then drawing said end to the left and 100 said second loop to the right to complete the bow tie.

2. That improvement in the art of forming a bow tie comprising the following steps: Laying the right end portion of a 110

ribbon or string over the rearwardly reaching left end portion thereof, forming a left loop or bow, then a right loop and then a left loop, from the overlying end portion of said ribbon, folding the underlying end portion of the ribbon forwardly over said loops, passing the end of said underlying portion under the body portion thereof and through the adjacent loop, and then drawing said end to the left and the right to complete the bow tie.

3. That improvement in the art of forming a bow tie comprising the following steps: Laying the right end portion of a ribbon or string over the rearwardly reaching end portion thereof, forming a plurality of loops or bows from the overlying end

portion of said ribbon, folding the underlying end portion of the ribbon forwardly 20 over said loops, passing the end of said underlying portion under the body portion thereof and through the adjacent loop, and then drawing said end to the left and the upper portion of said adjacent loop to the 25 right to tighten the bow tie.

4. A bow tie comprising an underlying portion and an overlying portion, a plurality of loops formed from said overlying portion, said underlying portion enwrapping 30 said loops and itself and being threaded through one of said loops.

In witness whereof, I hereby affix my signature this 26th day of April, 1922.

THOMAS A. QUINLAN.
